UNITED STATES PATENT OFFICE.

WILLIAM E. TRULL, OF JERSEY CITY, NEW JERSEY.

BUTTON-HOLE SEWING-MACHINE.

SPECIFICATION forming part of Letters Patent No. 320,448, dated June 16, 1885.

Application filed December 10, 1883. (Model.)

To all whom it may concern:

Be it known that I, WILLIAM E. TRULL, a citizen of the United States, residing at Jersey City, in the county of Hudson and State 5 of New Jersey, have invented certain new and useful Improvements in Button-Hole Sewing-Machines; and I do hereby declare the following to be a full, clear, and exact description of the invention, such as will enable others 10 skilled in the art to which it appertains to make and use the same.

My invention relates to certain novel and useful improvements in button-hole sewing attachments for sewing-machines, but is more 15 especially designed as an improvement on the construction shown and described in Letters Patent No. 211,932, granted February 4, 1879, to Samuel Rockwell, and No. 206,768, granted August 6, 1878, to Samuel J. Baird.

20 The object of my invention is to do away with the turret and the driving mechanism contained therein—such as is described and illustrated in said patents—and to provide means for effecting the oscillation and feeding 25 exceedingly simple and actuated by the movement of the needle-bar, whereby the attachment is more readily adapted to any sewing-machine; and with these ends in view my invention consists in the details of construction 30 and combination of elements hereinafter fully and in detail explained, and then specifically designated by the claims.

In order that those skilled in the art to 35 which my invention appertains may understand more fully its construction and operation, I will proceed to describe the same, referring by letters to the accompanying drawings, forming a part of this specification, in which—

40 Figure 1 is a vertical longitudinal section showing the arrangement of the operating-lever within the casing and the means for adjusting the same to regulate the sweep thereof; Fig. 2, a bottom view with the casing removed, 45 and Fig. 3 a similar view with all the parts removed except the gear-wheels and operating pawl and ratchet.

Similar letters denote like parts in the several figures of the drawings.

50 A is the main spur-gear or master wheel, which is on the same short shaft with a pinion, B, which meshes with the pinion C, all of

which are found in the Baird patent above mentioned. The master-wheel revolves a small pinion, D, and a cam-shaft, E, on which 55 it is fastened, precisely as in said Baird patent.

It is not deemed necessary to show by the drawings and herein particularly describe all the parts of a complete attachment—such as the horizontally oscillating or vibrating lever, 60 the cloth-clamp or fabric-holder reciprocated in the front end thereof, the cam-frame and the devices for operating the same to shift it from one side to the other of the button-hole and secure its ends, and to give longitudinal 65 movements to the cloth-clamp—said parts being fully shown and described in the patents above referred to.

My improvement relates only to the mechanism for actuating what is styled in the Baird 70 patent the "master-wheel," and in this respect it is materially different from the above-mentioned devices.

The side of the casing of the attachment is extended upward, as seen at F, (dotted line,) 75 and to this is pivoted by means of a screw, G, a lever, H, and heel piece I. To this heel-piece is attached a small plate, J, by means of a screw, K, a coil-spring, L, being placed between said heel and plate, so that the latter 80 has a slight spring movement laterally, as will be presently explained.

O is a pinion secured on the short shaft P and meshing with the master-wheel A. Q is a ratchet wheel arranged on the same shaft 85 with the pinion O and within the field of action of the plate J, which acts as a pawl on said ratchet.

R are set-screws passed through lugs M on the lever, against opposite sides of the heel I, 90 and by means of which the height of the lever H may be adjusted independent of the heel-piece, for the purpose of adapting the said lever in its normal position to different machines.

S is a set-screw by means of which the normal position of the heel-piece is varied, thereby increasing or decreasing the throw of the same, for the purpose presently explained. 95

The operation of my improvement is as follows: The extremity of the lever is attached 100 to the reciprocating needle-bar of a sewing-machine. As the lever is operated, each upward movement of the same will cause the heel-piece to be thrown forward, and the pawl

J will strike against one of the teeth of the ratchet Q and force the latter around. It will therefore be readily understood that at each complete reciprocation of the needle-bar the 5 ratchet will have been turned around one tooth, and the master-wheel and mechanisms in combination therewith will have performed their functions during said movement of the needle bar, in precisely the same manner and 10 with the same results as they do in the Baird patent, at each complete revolution of the shaft of the sewing-machine.

The teeth of the ratchet-wheel Q are so formed that when they have been acted upon by the pawl J their backs will extend in a plane parallel and contiguous with the side of 15 said pawl, as seen at Fig. 3, so that there can be no movement whatever of the wheel when in this relative position.

20 The operation of the lever continues as the needle-bar moves up and down, and the pawl J, as it moves backward out of contact with one tooth of the ratchet, springs inward, owing to the action of the coil-spring L, so that 25 it will be within the vertical plane of the next tooth, so that it will operate on the latter, as in the case of the previous tooth.

The great advantages gained by my invention are, that I not only do away with the expensive and inconvenient turret, thereby 30 greatly simplifying the construction, but also all the gears and operating parts in immediate relation therewith are in similar planes, and the transmitting of movement to the several 35 gears is of course accomplished with less power than where the gearing-wheels are in different planes.

I do not wish to be limited to the exact 40 shape of the lever shown, or to any particular way of attaching or connecting the same to the needle-bar, as in these respects the application of my invention may be varied.

Having described my invention, what I 45 claim as new, and desire to secure by Letters Patent, is—

1. In a button-hole sewing attachment, the combination, with the master-wheel of a series

of gears, such as shown, for actuating the oscillating and feeding mechanisms, of a ratchet and gear wheel mounted on the same short vertical shaft, and a pawl adapted to engage with said ratchet and attached to the lower extremity of a heel pivoted to an L-shaped swinging lever, substantially as set forth.

2. In a button-hole sewing attachment, the combination, with the ratchet-wheel and gear-wheel mounted on the same shaft, of the lever H, provided with adjustable means for controlling its oscillation, and having pivoted thereto the heel I, pawl J, secured to the heel, 50 spring L, interposed between said heel and pawl, and the master-wheel of a series of gears, such as shown, for actuating the oscillating and feeding mechanisms, substantially as set forth.

3. The combination of the pivoted lever H, capable of being reciprocated, heel I, pivoted to said lever, set-screws R, passed through lugs on said lever against opposite sides of 60 said heel, pawl J, secured to the lower extremity of the heel, spring L, interposed between said pawl and heel, ratchet Q, adapted to be actuated by said pawl and mounted on the same vertical short shaft with the pinion O, and the master-wheel of a series of gears, such 70 as shown, for actuating the oscillating and feeding mechanisms, substantially as shown and described.

4. In a button-hole sewing attachment, the combination, of the lever H, having pivoted thereto the heel I, pawl J, secured to said heel, ratchet and gear wheels mounted on the same shaft and adapted to communicate motion to the master wheel, and set-screws R, 80 passed through lugs on said lever against opposite sides of said heel, whereby the normal height of the lever may be changed, substantially as described.

In testimony whereof I affix my signature in presence of two witnesses.

WILLIAM E. TRULL.
